INVENTOR.

THOMAS C. ROBERTS.

BY.

K. A. Duckman

ATTORNEY.

UNITED STATES PATENT OFFICE.

THOMAS C. ROBERTS, OF LONG BEACH, CALIFORNIA.

AUTOMATIC GOLF-BALL TEE.

Application filed May 28, 1927. Serial No. 194,886.

1 An object of my invention is to provide a golf game in which the ball is automatically returned to position and is teed by a simple operation of the player.

5 Another object is to provide an automatic tee which will quickly and easily place the ball in playing position.

Other objects, advantages, and features of invention may appear from the accompanying drawing, the subjoined detailed description, and the appended claims.

In the drawing:

Fig. 1 is a perspective view of my tee in playing position.

15 Fig. 2 is a transverse sectional view of the same.

Fig. 3 is a fragmentary transverse sectional view of the teeing plunger in lowered position.

20 Fig. 4 is a view similar to Fig. 3 but with the plunger in raised position.

Fig. 5 is a fragmentary side elevation of the plunger control valve.

25 Referring more particularly to the drawing:

My automatic golf ball tee 1 is placed a suitable distance in front of a back-stop or target 2, against which the balls are adapted to be driven, and a tray, incline or the like, 30 3 is formed in front of the back-stop 2 to receive and collect the balls after they are driven.

An opening 4 is provided through the floor in the front of the tray 3 and a pipe 5 extends from the opening 4 to a vertical tube 6 set in front of the back-stop 2 at any convenient distance. The pipe 5 is set on an incline so that the balls will roll by gravity to the tube 6. A hole 7 is provided in the floor, which hole opens into the tube 6 and the golf balls 8 are adapted to pass through said hole as will be further described.

45 A plunger 9 is reciprocally mounted in the tube 6 and a golf tee 10 is secured to the top of the plunger 9. The tee 10 is preferably made of a section of rubber hose so that it will not break or mar the club when struck by the player. A cylinder 11 is mounted adjacent the tube 6 and a piston 12 is provided in said cylinder. A pitman 13 rises from the piston 12 and a link 14 is secured to the top of the pitman 13 and to the plunger 9. A slot 15 is provided in the side of the tube 6 to accommodate the link 14 and to permit the plunger 9 to move up-

wardly and downwardly following the movement of the pitman 13.

An oil pump 16 is driven by suitable means, such as the electric motor 17, and the intake for the pump is provided through a pipe 18 that extends from a sump 19. An outlet pipe 20 extends from the pump 16 to the bottom of the cylinder 11 and during the operation of the pump the liquid will be forced into the cylinder, raising the piston 12 and pitman 13, and carrying the plunger 9 upwardly to a point where the golf ball 8 rises through the hole 7 in a proper position to be struck by the player.

70 An outlet pipe 21 is provided in the top of the cylinder 11, said outlet pipe draining into the sump 19. Thus it will be seen that when the piston 12 rises above the pipe 21 that the liquid will flow through the pipe and will not raise the piston further. Thus I provide a gradual start and stop which will not dislodge the ball from the tee 10. The pump 16 operates continuously therefore the piston 12 will remain in a raised position.

75 When it is desired to carry a new ball into striking position the liquid in the cylinder 11 is drained therefrom as follows: A bell-crank lever 22 is pivoted under the floor and a pin 23 extends through the floor and bears against an arm of the bellcrank 22. A cable 24 is secured to the other arm of the bellcrank lever 22 and extends to a rack 25, which rack meshes with a gear 26 secured to the plug of a valve 27 on the bottom of the cylinder 11. Thus it will be seen that when the pin 23 is depressed the rack 25 will be moved upwardly to open the valve 27 and allowing the liquid in the cylinder 11 to quickly drain therefrom into the sump 19. Upon releasing the pin 23 a spring 28 bears against the rack 25 and closes the valve 27. The pump 16 again fills the cylinder 11 with liquid raising the piston 12 and carrying the ball 8 into striking position. Thus it will be seen that it is only necessary to depress the pin 23 when a new ball is desired.

80 Having described my invention, I claim:

1. An automatic golf ball tee comprising a hydraulic cylinder, means to supply liquid to said cylinder, a tee, means operatively connecting said cylinder and tee, and means to release the liquid from said cylinder when it is desired to depress the tee and replace a ball thereon.

2. An automatic golf ball tee adapted to be positioned in front of a target, a ball collector, a pipe extending from said ball collector, a hydraulic cylinder, pump means adapted to force liquid into said cylinder, a tee, means operatively connecting said tee and cylinder, said pipe extending to adjacent said tee, and means to release the liquid from said cylinder whereby the tee is depressed to receive another ball from the pipe. 50
3. An automatic golf ball tee adapted to be positioned in front of a stop, a ball collector, a pipe extending from said ball collector through which the balls are adapted to roll by gravity, a tube, a tee in said tube, a cylinder, a piston in said cylinder, means connecting said piston and tee, a pump connected to said cylinder, and manual means 15 to release the pressure in said cylinder whereby the piston and tee are adapted to be lowered so that a new ball is positioned on the tee. 65
4. An automatic golf ball tee adapted to be positioned in front of a stop, a ball collector, a pipe extending from said ball collector through which the balls are adapted to roll by gravity, a tube, a tee in said tube, a cylinder, a piston in said cylinder, means 20 connecting said piston and tee, a pump connected to said cylinder, and manual means to release the pressure in said cylinder whereby the piston and tee are adapted to be lowered so that a new ball is positioned on the tee, said manual means comprising a 25 valve on said cylinder, a pin adapted to be depressed by the player, and a cable extending from said pin to said valve. 70
5. An automatic golf ball tee adapted to be positioned in front of the back-stop, a ball collector, a pipe extending from said collector through which the balls are adapted to roll by gravity, a tube into which said pipe extends, a tee reciprocally mounted in said tube, a cylinder, a piston in said cylinder, a pitman extending from said piston, a link 30 connecting said pitman and tee, a fluid pump, a pipe extending from said fluid pump into the bottom of said cylinder, an outlet pipe extending from adjacent the top of said cylinder, and manually actuated means adapted 35 to release the fluid in said cylinder, said means comprising a valve in the bottom of said cylinder, a gear on said valve, a rack meshing with said gear, and manually operated means adapted to actuate said rack to open and close said valve. 80
6. An automatic golf ball tee adapted to be positioned in front of the back-stop, a ball collector, a pipe extending from said collector through which the balls are adapted to roll by gravity, a tube into which said pipe extends, a tee reciprocally mounted in said tube, a cylinder, a piston in said cylinder, a pitman extending from said piston, a link 40 connecting said pitman and tee, a fluid pump, a pipe extending from said fluid pump into the bottom of said cylinder, an outlet pipe extending from adjacent the top of said cylinder, and manually actuated means adapted 45 to release the fluid in said cylinder, said means comprising a valve in the bottom of said cylinder, a gear on said valve, a rack meshing with said gear, and manually operated means adapted to actuate said rack to open and close said valve. 85
7. An automatic golf ball tee adapted to be positioned in front of the back-stop, a ball collector, a pipe extending from said collector through which the balls are adapted to roll by gravity, a tube into which said pipe extends, a tee reciprocally mounted in said tube, a cylinder, a piston in said cylinder, a pitman extending from said piston, a link 50 connecting said pitman and tee, a fluid pump, a pipe extending from said fluid pump into the bottom of said cylinder, an outlet pipe extending from adjacent the top of said cylinder, and manually actuated means adapted 55 to release the fluid in said cylinder, said means comprising a valve in the bottom of said cylinder, a gear on said valve, a rack meshing with said gear, and manually operated means adapted to actuate said rack to open and close said valve. 90
8. An automatic golf ball tee adapted to be positioned in front of the back-stop, a ball collector, a pipe extending from said collector through which the balls are adapted to roll by gravity, a tube into which said pipe extends, a tee reciprocally mounted in said tube, a cylinder, a piston in said cylinder, a pitman extending from said piston, a link 55 connecting said pitman and tee, a fluid pump, a pipe extending from said fluid pump into the bottom of said cylinder, an outlet pipe extending from adjacent the top of said cylinder, and manually actuated means adapted 60 to release the fluid in said cylinder, said means comprising a valve in the bottom of said cylinder, a gear on said valve, a rack meshing with said gear, and manually operated means adapted to actuate said rack to open and close said valve. 95

In testimony whereof, I affix my signature.

THOMAS C. ROBERTS.
